CLAIM

The ornamental design for an electric fireplace, as shown and described.

DESCRIPTION

FIG. 1 is a perspective view of an electric fireplace showing my present design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged, fragmentary left view of a portion of FIG. 4;

FIG. 9 is an enlarged, fragmentary right view of a portion of FIG. 5;

FIG. 10 is a cross-sectional view taken along line 10-10 of FIG. 2;

FIG. 11 is a cross-sectional view taken along line 11-11 of FIG. 2; and,

FIG. 12 is a cross-sectional view taken along line 12-12 of FIG. 2.

The dashed broken lines represent unclaimed portions of the electric fireplace and form no part of the claimed design. The dashed broken lines depict portions of the electric fireplace and form no part of the claimed design.

Cross-hatching provided on cut surfaces is for illustrative purposes only and forms no part of the claimed design.

1 Claim, 12 Drawing Sheets
